UNITED STATES PATENT OFFICE.

HERBERT H. HEWITT, OF BUFFALO, NEW YORK, ASSIGNOR TO HEWITT RUBBER COMPANY, OF BUFFALO, NEW YORK, A CORPORATION.

DESIGN FOR A RESILIENT TIRE.

51,899.

Specification for Design.

Patented Mar. 26, 1918.

Application filed January 25, 1918. Serial No. 213,811. Term of patent 14 years.

To all whom it may concern:

Be it known that I, HERBERT H. HEWITT, a citizen of the United States, residing at Buffalo, in the county of Erie and State of New York, have invented a new, original, and ornamental Design for a Resilient Tire, of which the following is a specification, reference being had to the accompanying drawing, forming part thereof.

Figure 1 is a plan view of part of a re-

silient tire showing my new design. Fig. 2 is a view in cross section on line 2—2 of Fig. 1.

I claim:

The ornamental design for a resilient tire, as shown.

HERBERT H. HEWITT.

Witnesses:

EUGENE J. COLEMAN,

EDWARD H. HOCH.
